UNITED STATES PATENT OFFICE.

GEORGE B. LAMBERT, OF HUNTINGDON, TENNESSEE.

DEVELOPING BASKET.

Application filed December 17, 1920. Serial No. 431,386.

To all whom it may concern:

Be it known that I, GEORGE B. LAMBERT, a citizen of the United States, residing in the city of Huntingdon and State of Tennessee, have invented new and useful Improvements in Developing Baskets, of which the following is a specification, reference being had to the accompanying drawings.

This invention relates to developing baskets or racks, for use in developing, washing and fixing photographic films, and the object is to provide a simple, efficient and durable basket of this kind, for use in connection with the usual developing, washing and fixing tanks.

In the drawings:

Figure 1 is a side elevation of the basket loaded with films;

Figure 2 is an edge elevation;

Figure 3 is a plan view;

The invention consists of a rectangular frame 1, open at the sides, top and bottom, as shown, and provided with a lifting bail 2 pivoted at 3 to the frame 1. Across the top 25 of the frame 1 are permanently mounted a plurality of transverse bars 4, spaced apart, and from these bars the films 5 are suspended, by doubling the films at the center points

6 so that the ends straddle the bars 4 and depend below. Suitable releasable weights 7 30 may be provided, adapted to releasably grasp the lower ends of the films and thus hold them in the bath and from mutual contact. When the films are thus strung upon the basket they may readily be immersed in 35 the developing, washing and fixing tanks, as desired.

While I have herein described a certain specific method of constructing and assembling the elements of my invention, it is understood same may be varied in minor details, not departing from the spirit of my invention as defined in the appended claim.

What I claim to be new and patentable is:

A developing basket for photographic 45 films, the films being doubled at their central points; comprising an open rectangular frame; a plurality of transverse bars across the top of the frame adapted to support the doubled films; and releasable weights for 50 grasping the lower double ends of the films.

GEORGE B. LAMBERT.
